(57) **CLAIM**

What is claimed is the ornamental design for an animal enclosure, as shown and described.

DESCRIPTION

FIG. 1 is a right side perspective view showing the animal enclosure of Applicant's invention.

FIG. 2 is a left side perspective view of the animal enclosure of Applicant's invention.

FIG. 3 is a bottom perspective view of the animal enclosure of Applicant's invention.

FIG. 4 is a front elevation view of the animal enclosure of Applicant's invention.

FIG. 5 is a back elevation view of the animal enclosure of Applicant's invention.

FIG. 6 is a left side elevation view of the animal enclosure of Applicant's invention.

FIG. 7 is a right side elevation view of the animal enclosure of Applicant's invention.

FIG. 8 is a top view of the animal enclosure of Applicant's invention; and,

FIG. 9 is a bottom view of the animal enclosure of Applicant's invention.

The broken lines in the Figures depict environmental subject matter and form no part of the claimed design.
